ABSTRACT

A fuel compensating device for a supercharged type diesel engine comprising large and small pressure receiving members in chambers, a connecting member connecting the pressure receiving members, a lever connected with the connecting member whereby a stopped position of the control rack is displaced at positions corresponding to smoke limit at non-supercharging and high supercharging of the control rack and increased quantity position at starting.

3 Claims, 2 Drawing Figures

FIG. 1

FIG. 2

FUEL COMPENSATING DEVICE FOR A
SUPERCHARGED TYPE DIESEL ENGINE

The present invention relates to a fuel compensating device which is attached to a fuel injection pump and compensates, in response to supercharging air pressure, fuel supplying to a supercharged type diesel engine.

In a supercharged type diesel engine various devices for compensating fuel in response to variation of amount of supercharging air were already proposed. As these devices are exclusively directed to the compensating of heavy load and high speed, the compensating of low speed is not sufficient and particularly increase of fuel at starting is not effected automatically.

An object of the present invention is to provide a fuel compensating device which eliminates these defects and can effect supercharging in response to the requirements of an engine at low speed supercharging and engine starting.

Other objects of the present invention is to provide a fuel compensating device which is simple in construction and may be constructed as a unit so that it can be used in combination with an injection pump and a governor without disturbance of shape of the injection pump and kind and shape of the governor.

In order that the present invention may be more readily understood, reference will now be made to the accompanying drawing in which:

FIG. 1 is a vertical sectional view of an embodiment of the present invention and

FIG. 2 shows characteristic curves at idling of the engine and of the device shown in FIG. 1.

Referring now to FIG. 1, to a side surface of fuel injection pump 1 (to the other side surface of which is normally fixed a governor) is fixed a case 2 by bolts 3. The case comprises three stepped chambers, a large diameter chamber 4, an intermediate diameter chamber 5 and a small diameter chamber 6. To the large diameter chamber 4 is fitted a high pressure receiving member or a piston 7 which is movable stroke S. The outer portion of the small diameter chamber 6 and the inner portion integral with the intermediate diameter chamber 5 are partitioned by a low pressure receiving member or a diaphragm 8. The piston 7 and the diaphragm 8 are connected by a connecting member or a bolt 9. To a stepped portion at the intermediate portion of the bolt 9 is attached spring receiving washers 10 which are movable distance L in the direction of the piston 7 are engaged with the stepped portion by a compression spring 11. Between a stepped portion of the intermediate diameter chamber 5 and the piston 7 is mounted a compression spring 12 which urges the piston 7 to the right in FIG. 1. A boss 13 of the piston 7 abuts on the spring receiving washers 10 after the washers move distance L, forming a stopper against the action of the bolts 9 and thus the diaphragm 8. A lever 14 is swingably combined at one end with the bolt 9 by a pin 15 and supported on a pin 16 provided on the case 2 as a fulcrum and at the other end engages a fuel control rack 17 of an injection pump, forming a stopper against movement of the control rack 17 in the fuel increasing direction. Conducts 18 and 19 respectively are adapted to introduce engine supercharging pressure to the small diameter chamber 6 and the large diameter chamber 4.

The operation of this device is as follows:

The engine supercharging pressure is introduced through the conduits 18 and 19 to the large diameter chamber 4 and the small diameter chamber 6 and then the piston 7 compresses the spring 12 by the force responsive to area difference between the piston 7 and the diaphragm 8, moves the diaphragm 8 and the bolt 9 together stroke S to the left in FIG. 1 and is stopped abutting on the stepped portion of the large diameter chamber 4. In this time the spring 11 keeps distance L without compression due to set load so that the stroke S of the piston 7 is transmitted through the bolt 9 to the lever 14 which is swung anticlockwise and thus a stop position of the control rack 17 is determined accordingly. This is indicated on a line b in FIG. 2 in which abscissa is control rack position R and ordinate is engine rotation speed N. As supercharging pressure is further increased, the pressure in the small diameter chamber 6 acting on the deaphragm 8 over comes a set force of the spring 11 and moves the bolt 9 distance L to the right in FIG. 1, this being indicated on a line C in FIG. 2, so as to swing the lever 14 clockwise. Therefore the stop position of the control rack 17 is moved in the arrow direction (fuel increasing direction) in FIG. 1, this being indicated by a line d in FIG. 2. If supercharging pressure lowers from a state of the line b, the piston 7 acts stroke S to the right by the force of the spring 12 so that the stop position of the rack 17 moves in the arrow direction by the clockwise rotation of the lever 14. This is indicated by a line a or a' in FIG. 2. The spring 12 and a governor idling spring are adapted to have characteristic confirming to the requirement of the engine. For example a heavy set load of the spring 12 makes a characteristic the line a'. The line a shows fuel increase at the low speed and starting, the line b shows smoke limit at nonsupercharging, the line c shows fuel supercharge at high speed, line d shows smoke limits and line e shows upper limits of rotation in the control characteristic curve.

I claim:

1. A fuel compensating device for a supercharged type diesel engine, comprising three stepped chambers forming a case, a large pressure receiving member and a small pressure receiving member reciprocable in the chambers by supercharging air pressure of the engine and spring forces, a connecting member connecting the pressure receiving members coaxially and provided with springs therebetween and a lever serving as a stopper in the fuel increasing direction for a fuel control rack in a fuel injection pump and being connected with the connecting member so that in low supercharging pressure the small pressure receiving member and the connecting member are movable by movement of the large pressure receiving member and in high supercharging pressure the connecting member alone is movable by the small pressure receiving member.

2. A fuel compensating device according to claim 1 wherein a spring is provided between the large pressure receiving member and a stepped portion of the intermediate chamber.

3. A fuel compensating device according to claim 1 wherein an another spring is provided between the large pressure receiving member and a stepped portion of the connecting member.
